Albert Matson
S. W. Anderson
Attorney.

UNITED STATES PATENT OFFICE.

JOHN STOLPE AND ALBERT MATSON, OF MCPHERSON, KANSAS.

OIL-STOVE.

1,307,219.

Specification of Letters Patent. Patented June 17, 1919.

Application filed March 27, 1919. Serial No. 236,451.

To all whom it may concern:

Be it known that we, JOHN STOLPE, a subject of the King of Sweden, and ALBERT MATSON, a citizen of the United States, both 5 residents of McPherson, in the county of McPherson and State of Kansas, have made a certain new and useful Invention in Oil-Stoves; and we declare the following to be a full, clear, and exact description of the same, 10 such as will enable others skilled in the art to which it appertains to make and use the invention, reference being had to the accompanying drawing, and to letters or figures of reference marked thereon, which form a part 15 of this specification.

The figure of the drawing is a central vertical or longitudinal section of the invention as applied.

The invention has relation to oil stoves, 20 having for its object to provide means cooperating with the usual chimney of oil cooking stoves, which will deliver to the cooking vessel located thereabove a greater amount of heat for a given expenditure of 25 fuel, thereby saving a large proportion of fuel.

The invention consists in the novel construction and combinations of parts, as hereinafter set forth.

30 In the accompanying drawings illustrating the invention, the letter A designates the chimney used with an oil cooking stove of well known make, said chimney having at its lower end an inwardly extending flange provided with air-admitting perforations A', and at its upper end an inwardly extending flange A'', it being designed that this invention shall be an attachment for this chimney, being readily fitted thereto in 35 a comparatively short time.

In order to make sure that little or no heat shall escape by radiation from the chimney A, an annular lining D of asbestos is provided for the chimney within the same, being confined thereto by an inner annular sleeve F, the latter resting at its lower end upon the inwardly extending lower flange a 40 of the chimney, and at its upper end having contact with the inwardly extending upper flange A'', the lining D having similar extent, whereby both sleeve and lining are prevented from moving endwise and securely held in place at all times.

In order to protect the chimney from being 45 cooled by the outer or surrounding air, an outer annular lining C of asbestos is

placed in position therearound and confined thereto by an outer annular metal sleeve E, the latter having an upper contracted or tapered portion E', fitting closely against 50 the chimney, for a tight joint to cover up all indication or showing of the asbestos lining and to grip the chimney tightly to prevent any drop of the outer sleeve and lining through force of gravity or through accident. The lower end of the outer sleeve is also formed with a contracted or tapered portion E'', to hide all evidence of the outer asbestos lining and to similarly grip the chimney. It may be noted here that the 55 upper and lower inwardly extending flanges of the chimney overlie and underlie the inner asbestos lining at the ends, hiding all evidence thereof as well as of the inner sleeve.

The burner being lighted and the heated air being conducted upwardly through the chimney so that all of it is delivered to the cooking vessel, it is designed to further provide means to prevent unnecessary escape 60 laterally of the said heated air away from the said vessel, and to this end, an upper, upwardly-tapering, heat-concentrating frusto-conical sleeve G is placed over the top of the chimney upon the upper end of the outer sleeve E to bridge the space or joint between the chimney and the spider or skeleton support I for the cooking vessel, and concentrate the upwardly directed current of heated air against the bottom of said vessel. 65

For the same reason, that is to prevent unnecessary escape laterally of the heated air so conducted upwardly and delivered to the bottom of the cooking vessel, a lower downwardly-tapering heat-deflecting frusto-conical sleeve H is located below the upper sleeve, being oppositely tapered thereto and breaking joint therewith or lapping the same partially, the lower end of the lower sleeve resting upon an annular bead J near 70 the upper end of the outer sleeve E.

We claim:

1. In an oil cooking stove, the combination with a chimney having upper and lower inwardly extending flanges, of an inner annular lining of asbestos and an inner annular sleeve abutting at the ends against said flanges and resting upon the lower flange, an outer annular lining of asbestos and an outer annular sleeve the latter having an upper 100 contracted upwardly-tapering end portion gripping the chimney and closing in the end

- of said outer lining and a lower downwardly-tapering contracted portion also gripping the chimney and concealing the lining, an upper upwardly-tapering heat-concentrating 5 frusto-conical sleeve resting upon the upper end of the outer sleeve, and a lower downwardly-tapering heat-deflecting frusto-conical sleeve surrounding the outer sleeve and breaking joint with the upper frusto-conical 10 sleeve.
2. In an oil cooking stove, the combination with a chimney having upper and lower inwardly extending flanges, of an inner annular lining of asbestos and an inner annular 15 sleeve abutting at the en's against said flanges and resting upon the lower flange, an outer annular lining of asbestos and an outer annular sleeve the latter having an upper contracted upwardly-tapering end portion 20 gripping the chimney and closing in the end of said outer lining and having a lower an-

nular bead, and a lower downwardly-tapering contracted portion also gripping the chimney and concealing the lining, an upper upwardly-tapering heat-concentrating frusto-conical sleeve resting upon the upper end of the outer sleeve and bridging the joint between the same and the usual spider or skeleton support for a cooking vessel, and a lower downwardly tapering heat-deflecting 30 frusto-conical sleeve surrounding the outer sleeve, resting upon the upper bead thereof and breaking joint with the upper frusto-conical sleeve.

In testimony whereof we affix our signatures in presence of two witnesses. 35

JOHN STOLPE.
ALBERT MATSON.
